RAIL-ANCHOR.

1,116,722.

Specification of Letters Patent. Patented Nov. 10, 1914.

Application filed February 24, 1914. Serial No. 820,596.

To all whom it may concern:

Be it known that I, PHILIP W. MOORE, a citizen of the United States, residing at Evanston, in the county of Cook and State of Illinois, have invented certain new and useful Improvements in Rail-Anchors, of which the following is a specification.

My invention relates to rail anchors or anticreeping devices and particularly to devices of the wedge type.

10 A rail anchor of this type consists ordinarily of a pair of rail gripping members which have a wedging engagement one with the other, one of which members bears 15 against a cross tie and the other stands out of contact with said tie so that a forward creep or longitudinal movement of the rail, carrying with it the free member, produces a closer grip of the device on the rail base 20 whereby such forward creeping tendency is self-checked.

25 My invention has for one of its principal objects to provide a novel and improved rail anchor of the type above mentioned in which the co-engaging parts or jaw members are provided with two pairs of co-engaging wedge faces which become effective when the free member is moved in the direction of the tie, one pair of wedges operating to draw the jaws toward each other 30 so as to increase the lateral grip of the device on the rail, the other pair being designed to simultaneously increase the vertical pressure or clamping stress between the 35 parts of the device and the upper and lower surfaces of the base flange of the rail.

40 A further object of the invention is to provide in a device of the type described, an improved construction and arrangement of the parts whereby, if the anchor becomes a trifle loose on the rail, on account of vibration, unequal expansion and contraction as 45 between the rail and the anchor due to temperature changes or other causes, the parts of the anchor remain engaged with each other, this engagement obviating the danger of the parts of the anchor falling from the rail base when they become loosened.

50 The invention has for further objects such other improved constructions, arrangements and devices relating to rail anchors as will be hereinafter described and claimed.

The invention is illustrated, in a pre-

ferred embodiment, in the accompanying drawings, wherein—

55 Figure 1 is a side elevation of the device shown as applied to a rail, the latter being shown in section; Fig. 2, a plan view of the device shown in Fig. 1; Fig. 3, a longitudinal sectional view on line 3—3 of Fig. 1; Figs. 4 and 5, views, in perspective, of the two members constituting the anchor, and Fig. 6, a detail sectional plan taken on line 6—6 of Fig. 1, this figure showing particularly the wedging engagement operating to draw the jaw members toward each other.

60 Like characters of reference designate like parts in the several figures of the drawings.

Referring to the drawings, A designates a rail and B one of the cross ties supporting the same.

65 The anchor, in the preferred form shown, consists of two jaw members C and D. The jaw member C into the jaw of which the base flange of the rail fits snugly with a 70 binding engagement is formed with an arm or plate E adapted to extend across the under surface of the base flange of rail A to a point beyond the middle of the same terminating preferably, though not necessarily, 75 within the opposite edge of said base flange. It is formed with a downwardly projecting wedging rib or web F.

80 The jaw member D is formed with a slot G adapted to receive the edge of the base flange of rail A and with a slot H into which the rib F fits. The slot H and the rib F are oblique with respect to the longitudinal axis of the rail so that when the member D is moved toward the tie B its 85 jaw also approaches the jaw of the member C. Preferably, although not necessarily, the rib F and slot H are slightly dovetailed, that is, their coengaging wedge surfaces f, h have a slope from top to bottom toward the 90 center of the anchor. One of the jaw members, preferably the jaw member C, is formed with a strut or tie abutting flange J. In order to produce a vertical bind or clamp of the device upon the rail, as well as the 95 lateral clamp just described, the bottom surface h' of the slot H, and the corresponding surface f' of the rib have a slope downwardly toward the tie. Thus the tendency 100 of the rail to creep forward is checked by 105 the closer grip—both horizontal and verti-

cal—of the device on the rail which such creeping tendency induces. The efficiency of a device of this sort depends largely upon the capacity of the free member—member 5 D in this case—to move toward the tie when the rail starts to creep. If the friction between the free member and the fixed member is greater than the friction between the free member and the rail obviously this 10 necessary movement of the free member will not take place.

In the device shown I have provided for a close frictional grip of the free member on the rail base by forming said member 15 with a slot, the slot G, into which the edge of the rail base is wedged. Thus the free member completely surrounds or embraces the edge of the rail base, presenting three surfaces of contact therewith, the friction 20 between which and the co-engaged rail surfaces is amply sufficient to overcome the friction between the surfaces f, h, f', h'. The arm E on member C is relatively long in comparison with the projecting portion of 25 the member D which extends under and engages the extremity of said arm. This arrangement effectually prevents the device from dropping from the rail in case it becomes loose through vibration, difference in 30 contraction and expansion between the anchor and the rail due to temperature changes, or other causes. The short jaw member D extends under and holds up the end of the other member C so that the parts, 35 even though loose, are in proper position to resume their operative hold upon the rail with the change in temperature or when the creeping movement of the rail has moved the free member forward far enough to 40 take up the looseness. It will be seen that the wedging engagement between the two members takes place below, or very nearly below, the overlapping portion of jaw member D. The overlapping portion of the jaw, 45 therefore, takes up the wedging stresses which might otherwise break out or bend the edge of the rail.

While I have described my invention in certain preferred embodiments, some modification in the form and construction of the parts might be made without departure from the principles of the invention. Therefore I do not wish to be understood as limiting the invention to the precise constructions and arrangements shown and described except so far as the same are made specifically limitations in certain of the 55 claims hereof.

I claim:

60 1. In a rail anchor, the combination with a jaw member engaging one edge of the rail base and formed with an arm extending under the rail base beyond the middle thereof having a downwardly projecting rib; of a 65 jaw member which engages the opposite

edge of the rail base and is formed with a slot to receive said rib; said members being formed with co-engaging wedge faces and providing together means having a binding engagement with the top and bottom of the 70 rail base at both edges thereof, and one of them being provided with a tie-abutting portion.

2. In a rail anchor, the combination with a jaw member engaging one edge of the rail base, formed with an arm extending under the rail base beyond the middle thereof and having a downwardly projecting rib, said member being provided with a tie-abutting portion; of a jaw member which engages the 75 opposite edge of the rail base and is formed with a slot to receive said rib; said members being formed with co-engaging wedge faces and providing together means having a binding engagement with the top and bottom of the rail base at both edges thereof. 80

3. In a rail anchor, the combination with a jaw member adapted to engage one edge of the base flange of a rail and formed with an arm extending under the rail to a point adjacent the other edge of said base flange and provided at its extremity with a downwardly projecting rib, of a jaw member formed with a recess adapted to receive the 90 rib on said arm with a recess into which the adjacent edge of said base flange fits with a bearing at the top and bottom, one of said members being provided with a tie-abutting flange. 95

4. In a rail anchor, the combination with 100 a jaw member adapted to engage one edge of the base flange of a rail and formed with an arm extending under the rail to a point adjacent the other edge of said base flange and provided at its extremity with a downwardly projecting rib, of a jaw member 105 formed with a recess adapted to receive the rib on said arm and with a recess into which the adjacent edge of said base flange fits with a bearing at the top and bottom, said arm 110 provided with a tie-abutting flange.

5. A rail anchor comprising a pair of jaw members adapted to engage opposite edges of the base flange of a rail, one of said members provided with a relatively long 115 extension lying under said rail base and the other having a short extension which projects under said first named extension, said members being formed with co-engaging wedge faces and providing together a flat bearing for the base flange of the rail as wide as such flange and also jaws which engage the upper surfaces of said base flange above said flat bearing, one of said members being provided with a tie-abutting 120 portion. 125

6. A rail anchor comprising a pair of jaw members adapted to engage opposite edges of the base flange of a rail, one of said members provided with a relatively long ex- 130

tension lying under said rail base and formed with a tie-abutting flange, the other having a short extension which projects under said first named extension, said members being formed with co-engaging wedge faces and providing together a flat bearing for the base flange of the rail as wide as such flange and also jaws which engage the upper surfaces of said base flange above said flat bearing.

7. A rail anchor comprising a pair of jaw members adapted to engage opposite edges of the base flange of a rail and provided with extensions lying under said rail base, said extensions being formed with two pairs of co-engaging wedge faces, one of which operates to produce a horizontal and the other a vertical clamping of the device on the rail, one of said members being formed with a tie-abutting flange.

8. A rail anchor comprising a pair of jaw members adapted to engage opposite edges of the base flange of a rail and provided with extensions lying under said rail base, said extensions being formed under the rail and at one side thereof with two pairs of co-engaging wedge faces, one of which operates to produce a horizontal and the other a vertical clamping of the device on the rail, one of said members being formed with a tie-abutting flange.

9. A rail anchor comprising a pair of jaw members adapted to engage opposite edges of the base flange of a rail, one of said members having an arm extending under said base flange to a point adjacent the opposite edge thereof and terminating in a downwardly extending rib, the other member being formed with a slot to receive said rib, said rib and slot being constructed so as to provide co-engaging wedge faces and providing together a flat bearing for the base flange of the rail as wide as such flange and also jaws which engage the upper surfaces of said base flange above said flat bearing.

10. A rail anchor comprising a pair of jaw members adapted to engage opposite edges of a base flange of a rail, one of said members having an arm extending under said base flange to a point adjacent the opposite edge thereof and terminating in a downwardly extending rib, the other mem-

ber being formed with a slot to receive said rib, said rib and slot being constructed so as to provide two pairs of co-engaging wedge faces, one operating to produce a horizontal and the other a vertical grip of the device on the rail.

11. A rail anchor comprising a pair of jaw members adapted to engage opposite edges of the base flange of a rail, one of said members having an arm extending under said base flange to a point adjacent the opposite edge thereof and terminating in a downwardly extending dovetailed rib, the other member being formed with a dovetailed slot to receive said rib, said rib and slot being constructed so as to provide co-engaging wedge faces.

12. A rail anchor comprising a pair of jaw members adapted to engage opposite edges of the base flange of a rail, one of said members having an arm extending under said base flange to a point adjacent the opposite edge thereof and terminating in a downwardly extending dovetailed rib, the other member being formed with a dovetailed slot to receive said rib, said rib and slot being constructed so as to provide two pairs of co-engaging wedge faces, one operating to produce a horizontal and the other a vertical grip between the device and said rail base.

13. In a rail anchor, the combination with a jaw member comprising a jaw adapted to engage one edge of the base flange of a rail and formed with an arm extending under said base flange to a point between the middle of the same and its opposite edge and terminating in a downwardly extending rib, said arm being provided with a tie-abutting flange, of a jaw member formed with a slot adapted to receive said rib and with a slot to receive the adjacent edge of said rail base, said rib and first named slot being formed so as to provide two pairs of co-engaging wedge faces, one of which operates to produce a horizontal and the other a vertical grip of the device on said rail.
